SOLVENT EXTRACTION PROCESS

Edward F. Wadley, Baytown, Tex., assignor, by
mesne assignments, to Standard Oil Develop-
ment Company, Elizabeth, N. J., a corporation
of Delaware

Application March 22, 1948, Serial No. 16,185

7 Claims. (Cl. 196—14.19)

1

The present invention is directed to a method for extracting mixtures of hydrocarbons into their component parts. More particularly, the invention is concerned with an improved extraction method in which a wash oil is employed to allow more efficient separation of hydrocarbon mixtures into their component parts at subatmospheric temperatures.

Prior to the present invention, it has been known to employ solvents such as sulfur dioxide in the extraction of hydrocarbon fractions such as petroleum fractions boiling in the gasoline and kerosene boiling ranges. It has been further known to employ sulfur dioxide at subatmospheric temperatures of the order of -10° to approximately -60° F. in effecting separation of hydrocarbon mixtures into predominantly paraffinic and into predominantly aromatic fractions.

It has been known also that washing the extract phase from such solvent extractions with an oil of different boiling point and paraffinic in nature would allow recovery of substantially pure aromatic hydrocarbons. Such processes have been disclosed in U. S. 2,114,524 and U. S. 2,410,166 and have been very successful in making such separations. In fact, it has been possible by such techniques to recover substantially pure aromatic hydrocarbons from petroleum fractions.

The afore-mentioned type of solvent extraction process, in which sulfur dioxide has been employed as solvent, has also been employed in the extraction of synthesis naphthas such as those produced in the so-called Fischer-Tropsch process. However, the separations are favored by low temperature operations and it would be very economical and desirable to apply also the wash oil technique to such separations. In applying the so-called wash oil technique to such separations, it would be necessary to employ a wash oil having highly dissimilar characteristics to the synthesis naphtha to allow its ultimate separation and recovery in view of the wide-spread boiling range of the naphtha that is usually employed. It is usually customary to work with a naphtha from the so-called Fischer-Tropsch synthesis boiling up to about 450° F. This would necessitate employment of an oil boiling appreciably above 450° F. The skilled workman naturally turned to the fractions in crude petroleum having boiling ranges above about 500° F. However, it is impossible to employ temperatures below about 10° F. in solvent extraction when employing natural fractions from crude petroleum as wash oil, especially a fraction boiling above about 500° F., as is required. The reason the natural fractions cannot

2

be employed at low temperatures is that these fractions solidify or become very viscous at such temperatures and, therefore, become unsuitable for the purpose for which they are intended.

It is, therefore, the main object of the present invention to provide a process in which naphthas may be subjected to solvent extraction in the presence of sulfur dioxide and a wash oil which does not congeal and become viscous at the temperatures of the order of 0 to -100° F.

Another object of the present invention is to provide an improved method for solvent extracting hydrocarbon fractions boiling in the gasoline boiling range to obtain substantially complete separation between the predominantly paraffinic and the predominantly aromatic components of the hydrocarbon mixtures.

The present invention may be described briefly as involving the solvent extraction of a hydrocarbon mixture at a temperature between 0 and -100° F. to form raffinate and extract phases employing sulfur dioxide as the solvent. The extract phase is separated from the raffinate phase and subjected to countercurrent washing at a temperature in the range mentioned with an olefin polymer boiling in the range from about 500° to about 600° F. to cause removal from the extract by preferential solution of the hydrocarbons more nearly like the olefin polymer than the hydrocarbon preferentially dissolved in the solvent. In effect, the wash oil technique causes solution in the wash oil of the hydrocarbons similar to the olefinic polymer while the aromatic constituents remain dissolved in the solvent. This causes the formation of secondary raffinate and extract phases. The second extract phase contains substantially purified aromatics and other constituents of a similar nature soluble in the solvent.

The olefin polymer may be a polymer of any olefin such as a polymer of propylene boiling above about 450° F. or preferably between 500° and 600° F. For example, a polymer of propylene produced by contacting propylene with boron trifluoride may be useful in the practice of the present invention. Another olefin polymer which may be quite valuable in the practice of the present invention may be obtained from the naphtha itself which is being subjected to solvent extraction in accordance with the present invention. As a general rule, it may be stated that the polymer used in the present invention and having a boiling point in the range given should have a pour point no greater than about 0° F.

The synthesis naphtha produced by the hydro-

genation of carbon oxides in the presence of a catalyst such as an oxide or metal of the group VIII metals contains appreciable quantities of olefins, specifically alpha olefins which are quite useful starting materials for polymerization to synthetic lubricating oils. These naphthas also contain substantial quantities of oxygenated organic compounds, and, more recently, it has been discovered that these naphthas also contain aromatic and conjugated ring structure material.

The construction and impending construction in the United States of commercial equipment to produce synthesis naphthas in accordance with the afore-mentioned reaction will undoubtedly result in the employment of solvents such as sulfur dioxide to remove the oxygenated organic compounds from the synthesis naphthas since it is well known that such oxygenated organic compounds deleteriously affect the polymerization of the alpha and other olefins to lubricating oil polymers. Therefore, in accordance with a preferred mode of my invention, it is contemplated that the synthesis naphtha obtained as described may be extracted with sulfur dioxide at a low temperature of the order of 0 to -100° F. employing the so-called wash oil technique to obtain raffinate and extract phases. The raffinate phase, after freeing of sulfur dioxide, may be subjected to polymerization conditions to form a polymer, a large portion of which is suitable for use as a lubricating oil. It is contemplated that the polymer will be subjected to a separation treatment to separate the lubricating oil polymer from the lower boiling material boiling between about 450° to 600° F. This fraction may then be employed as the wash oil in the practice of the present invention in effecting a separation among the compounds dissolved in the extract phase.

In the practice of the present invention, it is contemplated that the solvent extraction will be carried out at a temperature in the preferred range between 0 and -60° F., but that lower temperatures as low as -100° F. may be employed. The amount of liquid sulfur dioxide may vary depending on the composition of the naphtha subjected to treatment. Usually, however, an amount of liquid sulfur dioxide in the range from about 50 to about 300 volume per cent based on the naphtha being extracted will be satisfactory.

The invention will now be described in further detail with reference to the drawing in which the single figure represents a mode of practicing the invention in which a naphtha produced in the synthesis by reacting carbon monoxide and hydrogen over an iron-containing catalyst is employed.

Referring now to the drawing, numeral 11 designates a feed line by way of which a hydrocarbon fraction obtained from the so-called Fischer-Tropsch synthesis is introduced into the system. The fraction introduced by line 11 will boil between about 100° and 450° F. This naphtha is suitably chilled and introduced to a solvent extraction zone 12 operated at a temperature in the range between 0 and -100° F. Leading to the top of solvent extraction zone 12 is line 13 by way of which liquefied sulfur dioxide at a similar temperature to that prevailing in zone 12 is introduced. The conditions prevailing in zone 12 causes a separation between the predominantly paraffinic and predominantly aromatic constituents. The olefins are not appreciably soluble in the liquid sulfur dioxide and find their way into the raffinate phase while the oxygenated organic compounds and aromatics are substantially solu-

ble in the solvent and are found in the extract phase. Thus, two phases are formed in zone 12, a raffinate phase and an extract phase; the raffinate phase is withdrawn by line 14 into a first solvent stripping zone 15 which is provided with a heating or temperature controlling means illustrated by coil 16 whereby conditions are adjusted in zone 15 for removal of sulfur dioxide which is withdrawn therefrom by line 17 for reuse in the process. The raffinate, substantially free of solvent, is withdrawn from zone 15 by line 18 and discharged thereby into a polymerization zone 19. Polymerization zone 19 is shown as a rectangle, but it will be understood to include all auxiliary equipment necessary for such polymerization operations. For convenience, polymerization zone 19 is provided with line 20 for introduction of a polymerization catalyst such as aluminum chloride and line 21 for withdrawal of spent catalyst such as aluminum chloride sludge.

The polymer is withdrawn from zone 19 by line 22 and routed through a treating zone such as a clay-treating zone 23 for removal of entrained sludge or other deleterious matter from the polymer. The clay-treated material then discharges from zone 23 by line 24 into a fractional distillation zone 25 which, for convenience, is shown as a single distillation tower, but may be a series of distillation towers. Zone 25 is provided with a heating means illustrated by coil 26 for adjustment of temperature and pressure. It will be understood that zone 25 will include suitable internal baffle equipment such as bell cap trays or other packing material which will allow intimate contact between vapors and liquids. Conditions are adjusted in zone 25 to remove unreacted hydrocarbons by line 27 and to obtain a fraction boiling in the range between 450° and 600° F. by line 28. Intermediate boiling fractions having lubricating oil qualities may be obtained by line 29 while a lubricating oil polymer may be withdrawn by line 30.

Returning now to the solvent extraction zone 12, the extract phase is withdrawn therefrom by line 31 and discharges thereby into the top of a wash tower 32 which is operated at a temperature substantially the same as that obtaining in zone 12. Into the bottom of wash tower 32 there is introduced by line 33 an olefin polymer boiling in the range between 450° and 600° F. which is obtained from line 28 in a manner as has been described. This polymer flows upwardly in tower 32 countercurrently to the extract introduced by line 31 and washes from the extract phase the constituents which are more soluble in the polymer than in the solvent. In effect, in wash tower 32 a secondary raffinate and a secondary extract phase are formed. The secondary extract phase is discharged from wash tower 32 by line 34 and will comprise aromatics and conjugated ring structure hydrocarbons. The raffinate phase will be removed from tower 32 by line 35 and discharged thereby into solvent stripping zone 36 which is provided with a heating or temperature controlling means illustrated by coil 37 for adjustment of temperature and pressure for removal of sulfur dioxide which is discharged from tower 36 by line 38 and is recycled to line 13 for admixture with sulfur dioxide introduced thereby into zone 12. At an intermediate portion of tower 36 there will be withdrawn by line 39 the material washed from the extract. Since this material will contain less oxygenated organic compounds than the feed stock, it may suitably

be recycled to extraction zone 12 by lines 39 and 40 as shown. It may be desirable, however, to discharge this stream from the system and this may be suitably accomplished by opening valve 71 in line 39. The bottoms fraction from stripper 36 will include the wash oil polymer, and it will be discharged therefrom by line 42 and may be recycled to tower 32 by branch line 43 controlled by valve 44. Line 43 connects into line 33. However, the wash oil polymer may, due to its continued exposure to heating in zone 36, polymerize or be subjected to thermal decomposition. Under these conditions, it may be desirable to discharge a portion of the material withdrawn by line 42 by opening valve 45 in line 46.

The amount of sub-lube polymer withdrawn by line 28 from distillation zone 25 may be in excess of that required for employment as a washing medium in tower 32. Provision is, therefore, made for discharge of a portion of this material by manipulation of valve 47 in line 28.

It will thus be seen from the foregoing description that a unitary process has been provided wherein a synthetic naphtha may be subjected to solvent extraction and polymerization in sequence and a portion of the polymer employed to increase the efficiency of the extraction step by employing the low-boiling portion of the polymer as a wash oil.

As mentioned before, the type of wash oil preferred in the practice of the present invention may be an olefin polymer such as a polymer of propylene. It will be apparent to the skilled workman that the polymers of the butylenes, pentylanes, hexylanes, and heptylenes may also be employed in lieu of a polymer of propylene. Propylene polymer produced by the boron trifluoride catalyzed polymerization of propylene at a temperature in the range between 80° to 200° F. is eminently suitable as a wash oil in the practice of the present invention. Such a polymer may have an aniline point of 175° F. with a pour point of less than -70° F.

As another example of a polymer which may be employed as a wash oil in the practice of the present invention is a polymer produced from the deoxygenated synthesis naphtha resulting from the hydrogenation of carbon oxides over an iron catalyst. Such deoxygenated synthesis naphtha, after polymerization with aluminum chloride, produces a polymer from which a fraction boiling at approximately 600° F. may be separated. Such a fraction separated from a polymerization of the type mentioned had the following inspection characteristics:

Viscosity at 210° F.	30.7 S. S. U.
O. C. flash	265° F.
Gravity	38° A. P. I.
Pour point	Below -50° F.

As a further example of the practice of the present invention, a fraction boiling between 160° to 450° F. of a synthetic naphtha containing 9.9 weight per cent oxygenated organic compounds was extracted at -50° F. with equal volumes of liquefied sulfur dioxide. This extraction yielded a raffinate amounting to 64% of the original feed and containing 2.8 weight per cent oxygen compounds. The extract resulting from the aforementioned solvent extraction without removal of solvent was then washed with a low pour point wash oil having the characteristics given in the foregoing table. Equal volumes of wash oil were employed based on the original charge to the solvent extraction at a temperature of -50° F. to

allow formation of a second raffinate containing the wash oil and 23 volume per cent of the original charge. This raffinate was distilled and separated into a synthetic naphtha fraction and a wash oil fraction. The material washed from the extract contained only 4.1 weight percent oxygenated organic compounds and was suitable, since it contained an appreciably lower concentration of oxygenated organic compounds, for inclusion as a recycle stream in the feed. In this operation in accordance with the present invention, the major portion of the oxygenated organic compounds was concentrated in the first extract and thus the extract contained substantially only aromatic hydrocarbons and oxygenated organic compounds which are easily removable from the aromatic hydrocarbons in accordance with the present invention.

The catalyst employed in the polymerization step in producing the olefin polymer having a boiling point in the range between 450° and 600° F. may be any one of the Friedel-Crafts catalysts such as boron trifluoride, aluminum chloride, zinc chloride, ferric chloride, titanium tetrachloride, zirconium chloride, and many others too numerous to mention.

The temperature at which the polymerization may be conducted may range from about 50° F. to about 250° F. A suitable temperature which will produce polymers having the desirable characteristics may range from 150° to about 175° F.

The nature and objects of the present invention, having been completely described and illustrated, what I wish to claim as new and useful and to secure by Letters Patent is:

1. A method for extracting a hydrocarbon mixture boiling in the gasoline boiling range which comprises admixing the hydrocarbon mixture with liquefied sulfur dioxide at a temperature in the range between 0 and -100° F. under conditions to form raffinate and extract phases, separating the extract phase from the raffinate phase, washing the extract phase with an olefinic polymer boiling in the range between 450° and 600° F. at a temperature in the range between 0 and -100° F. to form a second raffinate and a second extract phase, and recovering said phases.

2. A method for treating a hydrocarbon fraction comprising olefins, oxygenated organic compounds, aromatics, and conjugated ring structure hydrocarbons boiling in the gasoline boiling range which comprises subjecting a naphtha containing them to solvent extraction with liquid sulfur dioxide in an extraction zone at a temperature in the range between 0° and -100° F. under conditions to form a first raffinate and a first extract phase, separating said first raffinate and first extract phases, removing solvent from said first raffinate, subjecting said first raffinate to polymerization conditions in the presence of a catalyst capable of causing polymerization thereof to form a polymer, separating said polymer into a fraction boiling in the range from 450° to 600° F. and a fraction having lubricating oil characteristics, subjecting said first extract phase to contact with said polymer boiling in the range between 450° and 600° F. at a temperature in the range between 0 and -100° F. in a washing zone to cause the formation of a second raffinate and a second extract phase, separating said second extract phase and said second raffinate phase, subjecting said second raffinate phase to a separation treatment for recovery of sulfur dioxide, a fraction containing material dissolved in said

olefin polymer, and said olefin polymer, and recycling said fraction containing material separated from said olefin polymer and said olefin polymer, respectively, to the solvent extraction zone and the washing zone.

3. A method for treating a naphtha produced by a synthesis involving contacting a mixture of carbon monoxide and hydrogen with a hydrogenation catalyst which comprises separating the naphtha into a fraction boiling below 450° F., subjecting the naphtha boiling below 450° F. to solvent extraction with liquid sulfur dioxide in an extraction zone at a temperature in the range between 0 and -100° F., forming a first raffinate and a first extract phase, separating said first raffinate from said first extract phase, removing solvent from said first raffinate, subjecting said first raffinate to polymerization in the presence of a Friedel-Crafts catalyst under conditions to form a polymer boiling in the lubricating oil boiling range, separating said polymer into a fraction boiling in the range from 450° to 600° F. and a fraction having lubricating oil characteristics, admixing said first extract phase with said polymer boiling in the range between 450° and 600° F. at a temperature in the range between 0 and -100° F. in a washing zone, forming a second raffinate and a second extract phase, separating said second extract phase from said second raffinate phase, subjecting said second raffinate phase to distillation for recovery of sulfur dioxide, a fraction containing material dissolved in said olefin polymer, and said olefin polymer, and recycling said fraction containing material dissolved in said olefin polymer and said olefin polymer, respectively, to the solvent extraction zone and the washing zone.

4. A method for extracting a hydrocarbon frac-

tion comprising olefins, oxygenated organic compounds, aromatics, and conjugated ring structure hydrocarbons in the gasoline boiling range which comprises admixing said fraction with

5 liquefied sulfur dioxide at a temperature in the range between 0 and -100° F. under conditions to form raffinate and extract phases, separating the extract phase from the raffinate phase, washing the extract phase with an olefinic polymer 10 boiling in the range between 450° and 600° F. at a temperature in the range between 0° and -100° F. to form a second raffinate and a second extract phase, and recovering said phases.

15 5. A method in accordance with claim 4 in which the olefinic polymer is obtained by polymerizing an alpha olefin.

6. A method in accordance with claim 4 in which the olefinic polymer is obtained by polymerizing a fraction boiling below 450° F. obtained by contacting a mixture of carbon monoxide and hydrogen with a hydrogenation catalyst 20 at a reaction temperature and pressure.

7. A method in accordance with claim 4 in which the olefinic polymer has a pour point no 25 greater than about 0° F.
